MARKING MACHINE

Charles L. Sweyer, Columbus, Ohio, assignor to
 The Louis G. Freeman Company, Cincinnati,
 Ohio, a corporation of Ohio

Application May 27, 1932, Serial No. 613,981
 10 Claims. (Cl. 101—301)

This invention relates to marking machines or tracing machines particularly designed for use in shoe factories, for making impressions upon leather or other materials, for marking with an ink or pigment for ornamental purposes, or to place guide lines on the work for guidance of subsequent operations, or for any other purpose desired. Such machines are particularly adapted for operation upon skins, up-
 10 per blanks, or the like.

Such machines generally have a pad for supplying ink or other suitable marking material, a marking plate and a work positioning and supporting plate, all of substantially the same area. When the work in hand is of a small size, for instance women's shoes, a small machine is ordinarily used, but when the work is of a larger size, or of such a spread or nature as to require a larger support, e. g., strap shoes, as 20 distinguished from oxfords, a larger machine is used, and these machines are usually built with a bed or frame several times as wide as the size usually required for women's shoes.

In many factories equipped with small machines there is not enough work of large spread, to justify a larger machine, or there is insufficient room, and such work is marked by hand.

Accordingly, one of the objects of the present invention comprises an improvement in the 30 structure of the small style machine which will enable it to handle work heretofore requiring a structure of considerably increased size.

In attempting to utilize the relatively small work supporting plate in the small machine, it 35 sometimes happens that the parts to be marked extend beyond the area of the plate and not infrequently the weight of the unsupported work material is great enough to move it out of position on the plate, during a marking operation.
 40 Again, the work frequently extends to the side and in the path of links which carry the marking head and die from an inking position to a marking position, and when the marking head is moved toward the work, these supporting 45 links tend to displace the work from alignment on the positioning plate, with resultant spoilage of the work.

Ordinarily, in marking quarters, the dies and supporting plates are so made as to simultaneously mark both the left and right quarters, and it is on double dies of this kind that the greatest difficulties of properly laying out and supporting the work, are encountered.

It is an important object of the present invention to provide in a machine of this nature,

a structure which will avoid the foregoing objections by adequately supporting work of various sizes, in correct position, and free from interference of moving parts.

Another object of the present invention is to eliminate the need for hand marking or a plurality of different machines of variable size, in the provision of an arrangement whereby the small size machine conventionally used for small work such as women's shoes, may be utilized for larger work heretofore requiring a larger machine. To this end a novel supporting mechanism for the marking head, and an interchangeable series of work supporting plates are utilized, whereby to accommodate large or small plates without necessitating any change in size of the machine as a whole.

To the attainment of the above and other objects which will appear as the description proceeds, reference may be made to the accompanying drawings, in which:—

Fig. 1 represents a perspective of the machine, the work supporting plate being omitted;

Fig. 2 is a top plan of the machine bed with a small size work supporting plate in position;

Fig. 3 is a top plan of the machine with a large size plate in position.

Referring more particularly to the drawings, in which like reference numerals designate like parts, there will be seen a frame work or bed 1 having a pair of platforms 2 and 3 and a marking head 4 supported for movement between positions in which it engages one or the other of such platforms. The platform 2 is designed to receive the work e. g., a shoe upper blank to be marked by the machine, and the platform 3 supports an ink pad 5. A marking plate or die 9 (shown diagrammatically in Fig. 3) of substantially the same width and area as the pad 5 is detachably secured to the head 4 and with the head in the position illustrated in Fig. 1 such die will be inked by its engagement with the pad 5. Movement of the pad from inking position into engagement with the work on the platform 2 will effect an impression, or application of ink by the marking die, to the work.

If the marking is to consist of an impression only, the pad 5 may be omitted.

Supporting the head 4 for movement between the platforms, are pairs of links 6 and 7, pivotally attached to the head at each side thereof, said links being connected at their remote ends to the frame 1, and disposed in a substantially parallel relation. By this arrangement the head

- 4 may be moved from the position illustrated in Fig. 1 to a position in engagement with the work on the platform 2. A handle 8 is provided for manipulating the head 4.
- 5 Extending from the platform 2 are a series of studs 11, the purpose thereof being to locate and retain a work positioning and supporting plate. Fig. 2 illustrates a small size work supporting plate 12, the area of which is substantially equal 10 to that of the marking head 4, and ink pad 5, carrying abutment gauges 13 for accurately aligning the work with respect to the die and marking head.
- 15 Fig. 3 discloses a larger size marking plate 15 which likewise carries gauging abutments 13.
- It will be noted that the links 6 are spaced from the immediate sides of the machine and out of the vertical plane of the links 7 by the interposition of studs 16 and 17 between the 20 links and the sides of the marking head 4 and bed 1. The length of these studs is such as to accommodate the difference in width of the plates 13 and 15, it being evident that without such studs, the links 6 would be in the same 25 plane as the links 7 and adjacent the sides of the machine, whereupon if the plate 15, or a work piece of equivalent size were positioned in the machine the links 6 would strike the plate or work on the downward movement of the head 4.
- 30 Having thus described the machine, the use thereof will be readily apparent. When small work is to be marked, the plate 12 can be used and work positioned thereon by engagement with abutments 13 may be treated by first inking the 35 marking die at 5 and then manipulating the head 4 to bring the marking die in position to engage the work. When larger sizes of work are to be treated or small work requiring a large support as on straps, or the like, the small plate 40 12 is not used as the work would extend beyond its area and tend to slide over the sides thereof, due to its weight. Accordingly, the plate 15, is substituted therefor. In this instance, due to the extension of the plate over the base of the 45 machine, the larger spreads can be adequately supported and maintained in a substantially flat position, and at the same time the links 6 are sufficiently spaced to clear both the work and work supporting plate.
- 50 Advantages of this structure include obviation of the difficulties attendant on the small machine of the prior art, by inclusion of the studs 16 and 17, and also permits use of the small machine, which costs considerably less than the machines 55 now used for larger types of work, for the larger work. The work supporting plate 15 may be larger or wider than the supporting part of the machine on which it rests so as to support the work in a horizontal plane, and of course the 60 studs 16 and 17 can be made and sold at considerably less than the cost of the large machine. The one small size machine is thus able to do the work heretofore necessitating two different machines, or hand marking.
- 65 Having thus described my invention, what I claim as new and desire to secure by Letters Patent of the United States, is:—
1. In a marking machine, a marking head, a marking plate carried thereby, an ink applying member and a supporting member arranged to receive selectively, work supporting plates of varying widths, means supporting said marking head for movement from one of said members to the other, comprising a pair of links spaced apart a distance substantially equal to the width,

of the marking plate and connecting said marking head to the machine, and another pair of links pivoted below the plane of a selected work supporting plate and spaced apart a distance sufficient to clear the extreme side edges of such selected plate, regardless of width, and connecting said marking head to the machine.

2. In a marking machine, a frame, an ink applying station and a work marking station mounted in spaced relation to each other, a marking head, means supporting said head for movement from one station to the other, said marking station being arranged to receive selectively, work supporting plates of widths varying from a dimension approximating the width of the marking head to a dimension of substantially greater width, said supporting means including a member pivotally connected to the frame beneath said plate, and in spaced relation to the frame sufficient to clear the edge of the widest selected plate.

3. In a marking machine, a marking member, an ink applying station and a work marking station, means supporting said member for movement from one station to the other, said marking station being arranged to receive selectively, work supporting plates of widths varying from a dimension approximating the width of the marking member to a dimension of substantially greater width, said marking member supporting means including a link connected to said marking member and mounted on said frame in position to swing past the widest of said work supporting members.

4. In a marking machine, a marking member, means arranged to receive interchangeable work supporting members ranging from a width approximating that of the marking member to a width greater than said marking member, means supporting said marking member for movement in the machine comprising pairs of links pivotally connecting said member to the machine, and means interposed between the links of one pair and the elements to which they are connected effective to space said links from said elements a distance apart, equal to the width of the widest work supporting member, the remaining links being spaced apart a distance equal to the width of the marking member.

5. A marking device comprising two relatively movable members, means arranged to receive interchangeable work supporting devices and a marking device, ranging from a width approximating that of the marking device to a width greater than said marking device, means for attaching a selected one of said marking devices to one of said members, means for attaching said work supporting device to the other of said members, and means for supporting a movable one of said members in operative position, including an element connected to said movable member and pivoted on said frame in position to swing past the extreme side edge of the widest of said work supporting devices.

6. A device of the character described, comprising in combination, a base, a head, a marking element carried by said head, means connected to said base and supporting said head for movement to and from marking position, means arranged to receive interchangeable work supporting plates ranging from a width approximating that of the marking head to a greater width than said marking head, and the widest of said plates having portions projecting beyond a vertical plane at the point of connec-

- tion between said base and said supporting means, and means providing clearance between a portion of said supporting means and said projecting portions of the widest work supporting plate. 5
7. In a machine of the type described, a base, a marking station and a work supporting station on said base arranged to receive interchangeable work supporting devices of varying widths, a 10 movable marking head, and a plurality of guiding and carrying members connecting said head to said base for movement between said stations, certain of said members being spaced a greater distance from the sides of the base and 15 head than the others of said members, whereby to clear any selected device regardless of width, said latter members having their point of connection with the base located adjacent and below the work supporting station. 20
8. In a marking machine, a base, arranged to receive interchangeable work supporting devices of varying widths, a marking head and means connecting said head to said base for movement relative thereto, comprising a pair of links 25 pivotally connected to the sides of the head and to the sides of the base, a second pair of links and studs pivotally connecting said second pair of links to the sides of the head and base and effective to space said second pair of links from 30 the head and base. 95
9. In a marking machine, a base arranged to receive interchangeable work supporting devices of varying widths, a marking head and means connecting said head to said base for movement relative thereto including pairs of links pivotally connected to the sides of the head and the sides of the base, and studs interposed between such sides and the links of at least one pair thereby to space apart the latter links a distance greater than the distance between links of a remaining pair. 80
10. In a marking machine, a frame arranged to receive selectively, interchangeable work supporting plates of widths varying from a dimension substantially equal to the width of the frame, to a dimension of substantially greater width respectively, an ink applying member carried by the frame, a marking plate of a width substantially equal to that of the inking member, means mounting said plate for movement between said member and the selected surface including an element pivoted to the frame below said surface, and means to provide clearance between said element and an adjacent edge of said surface regardless of the width of the 100 surface. 90
